UNITED STATES PATENT OFFICE.

JOHN C. W. STANLEY, OF SANTA CRUZ, CALIFORNIA.

DISTILLING APPARATUS FOR KELP AND THE LIKE.

1,212,579.

Specification of Letters Patent. Patented Jan. 16, 1917.

Application filed March 7, 1916. Serial No. 82,578.

To all whom it may concern:

Be it known that I, JOHN C. W. STANLEY, a subject of Great Britain, residing at Santa Cruz, in the county of Santa Cruz, State of California, have invented new and useful Improvements in Distilling Apparatus for Kelp and the like, of which the following is a specification.

This invention relates to an apparatus for the destructive distillation of organic matter and the recovery of the volatile constituents therefrom.

Although I have described my invention as it is used for the destructive distillation of kelp or the like, it will be understood that my device may be used for distillation of any organic matter, such as kelp, wood or sawdust, peat, lignite, tannery waste, etc.

It is an object of this invention to provide an efficient apparatus in which destructive distillation may be continuously carried on in the absence of air and without any contaminating influences; so that the material may be constantly introduced to the apparatus and the solid and gaseous final products may be constantly withdrawn therefrom.

There are many minor objects of this invention, the accomplishment of which is set forth in specific form in the following specification, wherein I explain a preferred form of apparatus embodying my invention, reference being had to the accompanying drawings, in which—

Figure 1 is a plan, partially in section, of my improved apparatus; Fig. 2 is a longitudinal elevation and section taken as indicated by line 2—2 on Fig. 1; Fig. 3 is a section taken as indicated by line 3—3 on Fig. 1, and Fig. 4 is a detail section of a portion of the apparatus taken as indicated by line 4—4 on Fig. 1.

In the drawings the numeral 10 designates a suitable furnace housing constructed preferably with exterior and interior walls 11 and 12, the interior wall being made of fire brick and there being an air space between the two walls. This furnace is of any suitable size and configuration, and in its upper part I suspend a plurality of cast iron or other tubes 15, through which tubes the material to be distilled is slowly and uniformly carried by means to be hereinafter described.

In my preferred form and arrangement of apparatus the furnace is divided into two parts, one part at each end, by a central

transverse dividing wall 16, the tubes 15 passing directly through this wall. This central dividing wall 16 completely separates one end of the furnace from the other, 60 virtually making two distinct furnace spaces within the same housing. There are two combustion spaces 17 one on each side of the dividing wall 16, a fire door 18 providing access to each of the combustion chambers. The combustion chamber 17 is below the tubes 15. The flame and heated gases travel from the combustion chamber 17 under the tubes 15 horizontally back and around the rear end of a vertical baffle wall 70 19, as indicated by the dotted line arrows in Fig. 1, and then the heated gases travel upwardly through an opening 20 to the upper side of the tubes 15 and thence they travel rearwardly through space 25^a again 75 over the tubes as indicated by the full line arrows in Fig. 1 and again around the vertical baffle wall 19 through space 25, and then through the opening 21 into the stack 22. At the back part of the combustion chamber 80 17 there is a vertical baffle wall 23; and the chamber 17^a on the opposite side of the baffle wall 19 from the combustion chamber has a floor 24 higher than the floor of the combustion chamber, so that the cooling and 85 contracting gases of combustion are kept up against the tubes 15. The spaces 25 and 25^a above the tubes 15 are again smaller so that the gases are constantly kept in contact with the tubes to transmit their heat thereto. 90

As hereinbefore stated, the whole furnace contains two of the individual furnaces and combustion chambers thus described; and these furnaces keep the tubes and their contents at as nearly a uniform temperature 95 throughout as possible; so that the kelp or other material may be kept at a uniform temperature, said temperature being predetermined to thoroughly destructively distil the kelp, or other material. 100

The tubes 15 are preferably arranged in horizontal grouping, as shown; and one or more groups may be used, as desired. The tubes 15 join at their ends with boxes 30 and 30^a. These boxes are of practically 105 duplicate construction, and the section of one is shown in Fig. 4. The tubes are joined to the inner faces of the boxes as is shown in Fig. 1, being held thereto by any suitable means; a suitable asbestos or other gasket 110 may be introduced to make a tight joint under the conditions of temperature imposed.

Extending through each of the tubes and into and through the boxes I provide conveyer shafts 31, which may all be operated by gears from a single driving shaft 32 at 5 one end of the furnace, this driving shaft being operated by suitable means.

The shafts are journaled in bearings 29 on the outer sides or walls of the boxes, where they are kept comparatively cool. It 10 will be noted that the outer sides of the boxes are completely exterior of the furnace. The shafts all revolve in the same direction, as indicated in Fig. 4; each shaft has a spiral conveyer 35 fitting within the 15 tube so as to move the material in the tube longitudinally thereof. The conveyers are arranged alternately of opposite pitches so as to move the material in alternate tubes in opposite directions. The direction of 20 movement of material through the tubes is indicated by the arrows in Fig. 1.

The material is introduced through the feeder 40, shown in Fig. 4. This feeder preferably comprises a cone shaped hopper 25 41 in which I arrange a cone shaped spiral feeder 42, or other suitable device, upon a shaft 43 rotated by any suitable means, as through gears 44 from a driving shaft 45. This feeder is operated to feed raw material 30 into one end of the box 30 directly over one end of the spiral conveyer 35 at that end of the box. The feeder construction is such as to prevent access of air to the box and to the tubes. The material drops down onto 35 the conveyer 35 and is immediately and continuously carried rearwardly through the tube 15 toward the box 30^a. When the apparatus is in full operation the tubes are kept at a constant high temperature; and 40 the entering material is immediately carried into the highly heated tubes and is itself immediately heated to the constantly maintained temperature. A partition 46 prevents the material which drops from the feeder 45 from passing over to the next conveyer through the box; although it will be noticed that this partition does not extend to the top of the box. The material is carried to the rear end of the first tube 15 into one end 50 of the other box 30^a. The spiral screw conveyer 35 does not extend into the box 30^a at this end, but I place on the shaft in the box a paddle 47 which rotates with the shaft and acts to kick the material transversely 55 over into the next compartment of this box and into the next screw conveyer 35. A partition 46^a prevents the material being kicked transversely past the next conveyer. This next screw conveyer pitches oppositely 60 to the first one and carries the material forwardly to the front box 30 at the other end of the tubes 15.

At the forward end of the second shaft 31 there is a paddle 47, as shown in the section of Fig. 4, which acts to kick the material

over the low divide 40 in the bottom of the box into the next compartment of the box, where the material is picked up by the next conveyer 35 and is moved rearwardly through the next tube 15, being kicked over 70 transversely by the paddle 47 in the rear box, whence it is carried forward by the conveyer 35 through the last tube 15 again to the forward box 30. In the forward box 30 opposite the point of discharge of the 75 last conveyer I provide a discharge tube or the like, 50, through which the remaining solid matter finally passes. The character and quantity of this remaining solid material depends upon the nature of the initial material and upon the temperature and time period of treatment.

Now it will be seen that, although the boxes 30 and 30^a are provided with partitions 46 and 46^a which prevent the passage 80 of the solid material through the boxes except in the manner described, yet the boxes are open above the partition for the free 85 passages of gases. It is designed to keep the tubes 15 only partially filled with solid material, so that the gases generated may find exit at the ends of the tubes and thence into the box 30, whence they may flow through gas outlets 55 to any desired point. But it is a point in my apparatus that the 90 gases are not passed out immediately upon generation but pass first through the tubes to their ends and to the boxes and thence out. The gases are generated in the tubes, not in the boxes, for the tubes are kept at high temperature while the boxes are comparatively 95 cool.

It will be noted that the boxes are not at all within the furnace interior and that the end walls 10^a and top 10^b of the furnace 105 housing are cut away for placement of the boxes, so that the boxes are exposed to the exterior air to keep them cool. The gases in the boxes are therefore falling rather than rising in temperature; and, also, as has 110 been said before, the journal boxes 29 are kept cool. All these provisions enable me to keep up a proper temperature in the tubes 15 to obtain efficient distillation. The gases may be used as fuel for the furnaces or they 115 may be used as fuel for internal combustion engines, or as illuminating gas. For some purposes they may be enriched with oil, hydro-carbon or water or water-vapor, which may be introduced through a small 120 pipe 56 into one of the boxes 30 to act and mingle with the gases evolved. I find that in some cases, as in the treatment of seaweed or other organic matter, the addition of water or water-vapor assists and accelerates the elimination of the volatile constituents from the apparatus. The discharge 125 spout 50 may have an outwardly opening gate 60 held normally closed by the weight or other means, as illustrated at 61, which 130

gate will open to allow the outward passage of the solid products or will close to prevent inward passage of air. Constituents of value in kelp, or other organic matter are contained in the solid matter finally discharged; and this solid matter may be treated in any desired manner to separate out the valuable parts.

Having now described the preferred form 19 of my invention I claim:

1. In an apparatus for destructive distillation, the combination of a furnace, boxes arranged one at each end of the furnace, a plurality of tubes extending longitudinally 15 of and through the furnace and communicating at opposite ends with said boxes, means to move material back and forth through said tubes between the said boxes, means to introduce material to be distilled 20 into one of said boxes at the end of one of said tubes, means to discharge solid material from one of said boxes at the end of another of said tubes, and means to discharge gases from said boxes, said boxes having trans- 25 verse partitions separating the points of communication of the several tubes with the boxes, and said boxes being open above said partitions to allow free passage of gases.
2. In an apparatus for destructive distillation, a furnace, a pair of boxes arranged one at each end of the furnace, a plurality of tubes arranged in a common horizontal plane alongside of each other longitudinally 35 of and through the furnace and communicating at their opposite ends with said boxes, means for carrying material back and forth between the boxes through the tubes, said means embodying spiral screw conveyers one in each of said tubes and means to rotate 40 said conveyers all in the same direction, the conveyers in adjacent tubes being pitched in opposite directions so that material may be carried in opposite directions between the 45 boxes in adjacent tubes, means for feeding material to be distilled into one of said boxes over the end of one of said conveyers, a

paddle at the other end of said conveyer adapted to move the material from that end of the said conveyer transversely over to the conveyer in the next adjacent tube, vents 50 for gases from said boxes, and discharge means for the final solid product at the end of the tube through which the material is last conveyed.

3. In an apparatus for destructive distil- 55 lation, a furnace a pair of boxes arranged one at each end of the furnace, a plurality of tubes arranged in a common horizontal plane alongside of each other longitudinally of and through the furnace and commun- 60 icating at their opposite ends with said boxes, means for carrying material back and forth between the boxes through the tubes, said means embodying spiral screw conveyers one in each of said tubes and means to rotate 65 said conveyers all in the same direction, and bearings for said conveyers in the outer walls of said boxes; and said boxes being arranged with their outer walls exterior of the furnace so that the boxes and said bearings 70 may be kept comparatively cool, the conveyers in adjacent tubes being pitched in opposite directions so that material may be carried in opposite directions between the boxes in adjacent tubes, means for feeding 75 material to be distilled into one of said boxes over the end of one of said conveyers, a paddle at the other end of said conveyer adapted to move the material from that end of the said conveyer transversely over to the con- 80 veyer in the next adjacent tube, vents for gases from said boxes, and discharge means for the final solid product at the end of the tube through which the material is last con-veyed.

85

In witness that I claim the foregoing I have hereunto subscribed my name this 25th day of February 1916.
